UNITED STATES PATENT OFFICE.

ARTHUR ROBERTS, OF EVANSTON, ILLINOIS.

COKE-OVEN FOUNDATION.

1,259,133.

Specification of Letters Patent. Patented Mar. 12, 1918.

Original application filed September 8, 1914, Serial No. 860,583. Divided and this application filed February 23, 1915, Serial No. 10,043. Renewed June 22, 1917. Serial No. 176,426.

To all whom it may concern:

Be it known that I, ARTHUR ROBERTS, a citizen of the United States, residing at Evanston, in the county of Cook and State 5 of Illinois, have invented certain new and useful Improvements in Coke-Oven Foundations, of which the following is a specification.

The present invention has reference to 10 certain improvements in foundations for coke ovens and has reference in particular to the construction of said foundations and the arrangement of the flues for leading off the spent gases. The main object of the invention is to so arrange the flues and 15 passages that the spent gases will be collected uniformly from the entire lower portion of each heating wall and will be delivered from an entire bench of ovens uniformly to the 20 exhausting fans, stack, or other disposal connection.

Another feature of the invention has reference to a construction of the foundations such that they may be built up from stand- 25 ardized forms of block with a minimum amount of labor and with a minimum wastage of blocks in the construction.

Still another object of the invention is to 30 so construct the foundation and the spent gas take-off tunnels that the central portion of the foundation of the bench may be used for the accommodation of other features of construction, such as for the accommodation of preheating regenerators or the like, and 35 without the necessity of materially changing or modifying the essential planning of the foundation itself.

Other objects and uses of the invention will appear from a detailed description of 40 the same which consists in the features of construction and combinations of parts hereinafter described and claimed.

Referring to the drawings:

Figure 1 shows a vertical longitudinal section through the central portion of an oven and foundation embodying the features of 45 the present invention;

Fig. 2 shows an enlarged detail section of the lower portion of the construction shown 50 in Fig. 1, said section being taken on the line 2-2 of Fig. 1 looking in the direction of the arrows, the central oven being shown in section and the adjoining ovens in elevation;

Fig. 3 shows an enlarged plan detail of 55 one of the sole blocks;

Fig. 4 shows a side elevation of the block shown in Fig. 3; and

Fig. 5 shows a horizontal section taken on the line 5-5 of Fig. 1 looking in the direction of the arrows, the central portion of the 60 foundation being broken away for the purpose of shortening the figure.

In Fig. 2 I have shown the lower portions of three ovens and the foundation beneath them, the ovens being designated 6, 7 and 8, 65 respectively. The oven 7 with its foundation is sectioned on the line 2-2 of Fig. 1. The oven 7 is shown as having the heating walls 9 and 10, and for purposes of convenience the construction of these heating 70 walls is the same as that illustrated in Letters Patent of the United States No. 1,132,685, which was filed September 8, 1914, and issued March 23, 1915 and of which application this present application is a division. 75 The gases from each heating wall collect in a longitudinal passage 11 beneath said wall, and the gases for each oven travel from the passages 11 to a sole passage 12 beneath the oven. The passage 12 is formed 80 by a series of sole blocks 13, the construction of which is shown in detail in Figs. 3 and 4. Each of these blocks has a longitudinal 85 opening and a transverse opening which together form a Maltese cross, as is well shown in Fig. 3. The longitudinal openings of the sole blocks go to form the sole passage 12, and the transverse openings provide communication between the passages 11 and the sole passage. It will thus be seen that the 90 sole blocks perform the function of sustaining the load of the carbonizing chamber and also sustain the inner sides of the heating walls, as well as providing communication 95 from the passages 11 to the sole passage.

Beneath each sole passage is a transverse tunnel 14 which extends across the bench of ovens. A series of ports 15 establish communication between each sole passage and the corresponding tunnel 14 so that the spent 100 gases find their way into said tunnel uniformly throughout its length.

Underneath the sides of the bench are the tunnels 16 and 17. These collect the spent gases from the various ovens of the bench 105 and carry them to a suitable disposal apparatus, such for example as a fan or stack, or the boilers of a power house. The tunnels 16 and 17 are shown as communicating with the cross connection 18 which leads to the 110

disposal plant. The ends of the tunnels 14 connect with the bench tunnels 16 and 17 by means of the downcomers 19 and 20. The communication between each of the tunnels 14 and its downcomers may be controlled by the dampers 21. These dampers may be adjusted back and forth so as to equalize the draft in the heating walls of all of the ovens of a bench notwithstanding the fact that some of said ovens are farther from the draft producing means than others.

It will be seen from an examination of Figs. 1 and 5 that the tunnels 16 and 17 lie close to the sides of the bench and underneath the end portions of the ovens. It will also be observed that the central portions of the ovens are sustained by a longitudinal pier or the like 22 between the tunnels 16 and 17. By placing the tunnels at the sides 20 of the bench in the manner described, the connections from the tunnels 14 to the tunnels 16 and 17 are shortened up and at the same time a considerable space is left beneath the central portion of the bench of ovens, unoccupied except by the pier 22 or any other suitable appliances or mechanisms which may be built into said space. In other words, there is left available a considerable space for the accommodation of other appliances. In my co-pending application for Letters Patent of the United States on improvements in regenerative coke ovens, Serial No. 10,041, filed in the United States Patent Office February 23, 1915, I have 35 shown an oven construction in which this space is utilized for the accommodation of regenerators for preheating the air when it is desired to use such an arrangement. It is evident that this space might be used for the 40 accommodation of other constructions than regenerators, if so desired.

While I have herein shown and described only a single construction embodying the features of my invention, still it will be evident that many other constructions might be devised or adopted without departing from the spirit of the invention.

I claim:

1. The combination with a bench of coke ovens having heating walls, of a foundation on which said coke ovens are mounted, there being a passage for spent gases located immediately beneath and extending throughout the length of each heating wall for the purpose of collecting spent gases from the entire lower portion of said wall, a sole passage beneath the sole of each oven and extending throughout the length of the oven, a plurality of gas connections from the spent gas passages of each oven to the sole passage of said oven, a transverse tunnel beneath each sole passage and extending across the bench, a plurality of connections from each sole passage to the corresponding transverse tunnel, a spent gas tunnel underneath each side

of the bench, and downcomers from the ends of the transverse tunnels to connect the same with the spent gas tunnels, whereby there is provided a space beneath the central portions of the ovens of the bench, and beneath the spent gas tunnels thereof. 70

2. The combination with a bench of coke ovens having heating walls, of a foundation whereon said ovens are mounted, said foundation having a spent gas tunnel extending 75 along each of its side portions and beneath the ends of the ovens, the base portion of each oven being provided with a spent gas passage underneath each of its heating walls and with a sole passage underneath its carbonizing chamber and with a transverse tunnel underneath its sole passage, there being a plurality of cross connections from the spent gas passages of each oven to the sole passage thereof and a plurality of vertical 80 connections from each sole passage to the corresponding transverse tunnel, and there being a downcomer from each end of each transverse tunnel to the adjacent spent gas tunnel. 85

3. The combination with a bench of coke ovens having heating walls, of a line of sole blocks beneath the sole of each oven serving to support the carbonizing chamber and the interior portions of the heating walls of said oven, there being a spent gas passage at each side of said line of sole blocks, each sole block being provided with a longitudinal opening and a transverse opening communicating with each other in the form of 95 a Maltese cross, the longitudinal openings of the sole blocks together constituting a sole passage and the transverse openings of said blocks establishing communication from the spent gas passages to said sole passage, there 100 being a transverse tunnel underneath each sole passage and a plurality of vertical connections from each sole passage to the corresponding tunnel, a spent gas tunnel underneath each side of the bench of ovens and lying 105 below the ends of the ovens, and a downcomer from each end of each transverse tunnel to the spent gas tunnel. 110

4. A foundation for a bench of coke ovens, said foundation being provided with a spent 115 gas tunnel in each of its side portions, said tunnels extending throughout the length of the foundation, and the foundation being provided with a plurality of downcomers located outside of the tunnels, the lower end 120 of each downcomer communicating with the adjacent tunnel.

5. The combination with a bench of coke ovens having heating walls, of a line of sole blocks beneath the sole of each oven serving 125 to support the carbonizing chamber of said oven, there being a spent gas passage at each side of said line of sole blocks adapted to receive spent gases from the corresponding heating wall, each sole block being provided 130

with a longitudinal opening and a transverse opening communicating with each other in the form of a Maltese cross, the longitudinal openings of the sole blocks together constituting a sole passage and the transverse openings of said blocks establishing communication from the spent gas passages to said sole passage, a spent gas tunnel underneath each side of the bench of

ovens and lying below the end portions of the ovens, and a downcomer from each end of each transverse tunnel to the adjacent spent gas tunnel.

ARTHUR ROBERTS.
